Des. 228,768
Patented Oct. 23, 1973

228,768

VEHICLE AIR CONDITIONER

Edward John Borowiec, Rockford, Ill., assignor to Kysor
Industrial Corporation, Cadillac, Mich.

Filed Feb. 9, 1972, Ser. No. 225,028

Term of patent 14 years

Int. Cl. D23—04

U.S. Cl. D23—142

FIG 1

FIG 2

FIG 3

FIG 4

FIG. 1 is a front elevational view of a vehicle air conditioner showing my new design;

FIG. 2 is a bottom plan view thereof;

FIG. 3 is a rear elevational view thereof; and

FIG. 4 is a reduced scale right-end elevational view thereof.

I claim:

The ornamental design for a vehicle air conditioner, substantially as shown and described.
